US0D1070629S

(12) United States Design Patent (10) Patent No.: US D1,070,629 S
(45) Date of Patent: * Apr. 15, 2025

(54) WRISTWEAR

(71) Applicant: Daniel M. Carmi, Bal Harbour, FL (US)

(72) Inventor: Daniel M. Carmi, Bal Harbour, FL (US)

() Term: 15 Years

(21) Appl. No.: 29/813,227

(22) Filed: Oct. 27, 2021

(51) LOC (15) Cl. 10-07

(52) U.S. Cl.

USPC D10/128

(57) CLAIM

The ornamental design for wristwear as shown and described.

DESCRIPTION

FIG. 1 is a top front perspective view of the wristwear embodying my new design;

FIG. 2 is another top front perspective view thereof;

FIG. 3 is a front view thereof;

FIG. 4 is a back view thereof;

FIG. 5 is a top view thereof, from which the bottom view is a mirror image;

FIG. 6 is a side view thereof, from which the other side view is a mirror image;

FIG. 7 is top side perspective view thereof; and,

FIG. 8 is another top side perspective view thereof.

The broken lines shown in the drawings illustrate portions of the wristwear that form no part of the claimed design.

1 Claim, 6 Drawing Sheets
